UNITED STATES PATENT OFFICE.

GEORGE W. BLAIR, OF MISHAWAKA, INDIANA, ASSIGNOR TO MISHAWAKA RUBBER & WOOLEN MANUFACTURING COMPANY, OF MISHAWAKA, INDIANA, A CORPORATION OF INDIANA.

WATERPROOF SEAM AND METHOD OF MAKING SAME.

Application filed December 15, 1924. Serial No. 755,830.

My invention has reference to the waterproofing of stitched seams and is particularly useful in connection with articles of footwear.

5 It is a common practice to make heavy shoes of leather or part leather and part rubber, waterproof so that they keep out the moisture in wet weather and when used in wet places. It has been found, however, that 10 the stitched seams in shoes of this character oftentimes are not entirely waterproof, as the water and moisture works its way between the lapped edges and through the openings through which the stitches are 15 passed. It is the purpose of this invention to avoid this leakage in footwear by providing a method and means for thoroughly sealing the lapped joint and the openings through which the stitches are passed.

20 On the drawings:

Fig. 1 is a side view of a shoe embodying my invention;

Fig. 2 is an enlarged sectional view on the line 2—2 of Fig. 1; and

25 Fig. 3 is a section very much enlarged, taken on the line 3—3 of Fig. 1.

Referring to the drawings, the reference numeral 1 indicates the foot portion of a shoe, said portion being made of rubber in 30 the particular shoe which is illustrated, and preferably provided with a fabric lining 2 on the inner side. The upper 3 of the shoe is made of leather and consists of quarters which may be unitary or sewed together 35 along their rear edges, as shown, with a tape 4 overlying the joint, and these quarters have their front edges secured to a tongue 5, which is usually of a bellows form.

It is customary in shoes of this character, 40 to secure the upper 3 to the foot portion 1 of the shoe by a number of lines of stitches 6, a tape 7 of fabric being usually interposed between the two parts so that the oil from the leather will not injuriously affect the 45 rubber of the foot portion 1. The stitching of the upper to the foot portion does not always draw the parts together tight enough to form a waterproof joint, and as the stitching is made with rather coarse thread so as 50 to insure a substantial connection, it sometimes happens that the openings through which the threads are passed, are not closed up sufficiently tight to prevent water leaking therethrough. Moreover the water or mois-

ture which works its way into the stitch 55 openings does not dry out readily and has an injurious effect on the thread. To avoid these disadvantages I employ a tape 8 of rather soft or rich rubber, which is interposed between the foot portion 1 and the 60 upper 3, preferably being laid directly over the fabric tape 7, and when the stitching 6 is applied and the stitches drawn up tight in the usual manner, this rubber tape 8 is compressed sufficiently to insure a tight joint 65 and it also packs around the threads 6 and forms an effective sealing of the stitch openings. As a matter of fact, it has been found in practice that the rubber presses out through and packs the stitch openings in the 70 leather upper 3 as indicated at 9 in Fig. 3 and protrudes slightly from the outer ends of the stitch openings. This has a further effect of preserving the threads as the sealing of the openings in the leather upper 3 75 prevents the moisture from penetrating into the stitch openings where it naturally dries more slowly than on the exterior and affords a greater opportunity therefore for rotting 80 of the threads.

It is to be understood that this waterproofing may be employed at any points where stitching or other fastening of the parts together affords openings through which leakage may occur. In practice a 85 strip 10 of soft rubber is interposed for sealing purposes between the strip 4 at the back of the shoe and the upper 3, and this rubber sealing is also applied between the lower portion of the tongue 5 where it is 90 connected with the foot portion 1 and also where the tongue is connected to the lower portion of the upper 3 so as to insure a perfect waterproof connection between the foot portion 1 and the upper portion of the 95 shoe.

While I have shown and described my invention in a preferred form, I am aware that various changes and modifications may be made without departing from the principles 100 of my invention, the scope of which is to be determined by the appended claims.

I claim as my invention:

1. The method of connecting a layer of leather and a layer of rubber to form a 105 waterproof joint which comprises interposing a strip of softer rubber between the layer of leather and the layer of rubber, and in-

terposing a strip of fabric between the strip of soft rubber and the layer of rubber and then applying a plurality of rows of stitches through the layers of leather and rubber and the strips of soft rubber and fabric and thereby compressing the soft rubber and forcing portions thereof into the stitch openings of the layer of leather.

2. In a shoe, a foot portion, an upper having its lower edge overlapping the top of the foot portion, a thick soft rubber sealing element between the overlapped portions of said upper and said foot portion, and a plurality of substantially parallel rows of stitches extending through the overlapped upper and foot portion and also through the soft rubber and holding said parts under compression, the outer ends of the stitch-openings being exposed at the exterior of the shoe portions of said rubber sealing element being extruded by the compression into and closing the ends of the stitch openings.

3. A shoe seam, comprising overlapped shoe upper members, a thick soft rubber seal-

ing element between the overlapped shoe members, and a plurality of substantially parallel rows of stitches extending through the overlapped shoe members and the rubber sealing element and holding said parts under compression, the outer ends of the stitch-openings being exposed at the exterior of the shoe, portions of said rubber sealing element being extruded by the compression into and closing the ends of the stitch openings.

4. The method of forming a stitched waterproof shoe upper seam wherein the outer ends of the stitch-openings are exposed at the exterior of the shoe, which consists in interposing a soft rubber sealing element between overlapped shoe members, and stitching a plurality of substantially parallel rows of stitches through the overlapped shoe members and the sealing element and drawing the stitches tight and thereby extruding portions of the sealing element into and closing the ends of the stitch openings.

GEORGE W. BLAIR.
